UNITED STATES PATENT OFFICE.

ELVAH O. BULMAN, OF GRAND RAPIDS, MICHIGAN.

DISPLAY RACK.

Application filed March 7, 1927. Serial No. 173,255.

This invention relates to a display rack and is concerned with the production of a very practical, rigid and durable display rack, made in a very simple manner at low cost.

5 It is a primary object and purpose of the present invention to make a display rack and equip the same with tilting shelves or shallow pans which are mounted on spaced apart supporting posts or standards and so construct the rack that the attachment of the shelves or pans to the posts gives sufficient strength and rigidity that it is not necessary to use any reinforcing cross bars or braces between the spaced apart vertical posts. This 10 eliminates a considerable item of expense without detriment to the rack.

To this end, as well as many others not at present stated, I have made the invention fully described in the following description 20 and shown in the accompanying drawing, in which,

Fig. 1 is a front elevation of the rack.

Fig. 2 is a vertical section taken therethrough between the ends of the rack, and 25 Fig. 3 is a fragmentary enlarged vertical section illustrating the tilting mount of a shelf or pan on a post.

Like reference characters refer to like parts in the different figures of the drawing.

30 In the construction two spaced apart vertical posts 1 are used, the same being, preferably, made of channel iron for strength and elimination of weight. The flanges of the channel extend outwardly. At the lower 35 end of each of the posts 1 a horizontal bar 2, which also may be of channel iron, is permanently attached, said bars being attached at the inner sides of the post. Adjacent each end each bar 2 is equipped with a castor 3.

40 Located directly above and resting upon the upper flanges of the bars 2 is a shallow pan made of sheet metal having a horizontal bottom 4, vertical ends 5 and vertical sides 6, which are bent inwardly back upon themselves, as indicated at 7, so as to strengthen and reinforce the pan or shelf and make smooth upper edges. It is also apparent that the ends 5 may be bent back upon themselves in the same manner so that the upper 45 edges of the sides and ends of each pan or shelf are smooth and present no rough edges. This pan or shelf is longer than the distance between the posts 1 and openings are made in the bottom 4 through which the posts pass.

50 At the upper ends and at a plurality of points below said upper ends other similar

shelves or pans of identical construction, except for size, are located and mounted for tilting adjustment. Each of these upper shelves or pans has a bar 8 of angle iron permanently secured at two spaced apart points transversely of and at the under side of its bottom 4. The angle bars 8 are spaced apart a distance such that their downwardly extending vertical legs lie against the inner 60 sides of the posts 1 when any shelf or pan is applied to said posts. These shelves likewise are provided with openings in their bottoms 4 so as to slide downwardly on the post and permit tilting. Pivot bolts 9 pass 65 through the webs of the posts 1 and through the vertical legs of the angle 8 so that the shelves or pans may be turned about a horizontal axis to different angular positions.

Connected to the vertical legs of each of the 70 angle bars 8 is an arc-shaped bar 10 substantially semi-circular in form. The ends 10^a, as shown in Fig. 3, are off-set so as to come against the inner sides of the vertical legs of the bars 8 one at each side of the pivot 9 of any 75 bar. The off-set end portions 10^a are permanently secured to the bars 8 by welding, riveting or other equivalent fastening means. In the curved arc portions of each of the members 10, a plurality of openings 11 are made 80 in substantial alignment with each other, the same being spaced apart and adapted to come into conjunction, any one of them, with an opening made through the web of the adjacent post 1. A bolt 12 may be passed through 85 openings which are in conjunction or alignment and thereby hold the pan or shelf in any position to which it has been adjusted. It may be held horizontal, one of which is shown between the upper and lower ends of 90 Fig. 2.

This construction of display rack has proved very practical. By reason of the rigid attachment of the angle bars 8 to the under sides of the shelves or pans said bars in 100 turn having a pivotal mounting at 9 on the vertical post, the shelves serve not only as shelves but as brace or cross members between the vertical posts 1. This is helped by the connection of the metal curved members 10 105 which come snugly against the inner sides of the posts 1 and are secured thereto by the bolts 12. It is not necessary to use any additional cross bracing, the rack being strong and rigid and fully capable of withstanding 110 the usage to which it is put, when constructed as described. The invention is defined in the

appended claim and is to be considered comprehensive of all forms of structure coming within their scope.

I claim:

- A display rack comprising spaced apart vertical posts, horizontal bars attached substantially midway between their ends to the lower ends of said posts, a shelf having openings therethrough for the passage of the 10 posts lying against the upper side of said horizontal bars, a second shelf located at the upper ends of and between said posts, transverse bars attached to the under side of said shelf, means pivotally connecting said bars

to the posts, and members semi-circular in 15 form attached one to each of the transverse bars and extending downwardly therefrom and lying against the inner sides of said posts, said members having a plurality of spaced apart openings therethrough and said 20 posts having openings therethrough under the openings in said members, and a bolt to pass through the openings in said posts and the openings in said members, substantially as described.

25 In testimony whereof I affix my signature.

ELVAH O. BULMAN.
